Primary Examiner — Susan E Krakower*Assistant Examiner* — Christina M. Dodson(74) *Attorney, Agent, or Firm* — Thorpe North & Western, LLP(57) **CLAIM**

The ornamental design for the fluted glass candle warmer lamp as shown.

DESCRIPTION

FIG. 1 is a perspective view of the fluted glass candle warmer lamp in accordance with our invention;

FIG. 2 is a front elevation view thereof;

FIG. 3 is a rear elevation view thereof;

FIG. 4 is a right side elevation view thereof;

FIG. 5 is a left side elevation view thereof;

FIG. 6 a top plan view thereof; and,

FIG. 7 is a bottom plan view thereof.

The portions of the fluted glass candle warmer shown in broken lines form no part of the claimed design.
